HAIR COLLECTING APPARATUS

Morris Hartzman, Dubuque, Iowa

Application June 30, 1937, Serial No. 151,293

1 Claim. (Cl. 132—9)

This invention relates to hair collecting apparatus and has for an object to provide a vacuum operated hair receiver adapted to be applied to a barber's chair and to embrace the neck of the customer at the shoulder level to remove hair as it is being cut by the barber and convey it away thus eliminating the annoying hair deposit upon the towel and frequent brushing of loose hair from the head.

10 A further object is to provide a device of this character having a conventional suction device and collecting bag which may be connected to the pipe line receiving hair from the various chairs and will be inconspicuous when installed.

15 A further object is to provide a device of this character which will be formed of a few light strong and durable parts, which will be inexpensive to manufacture, and which will not easily get out of order.

20 With the above and other objects in view the invention consists of certain novel details of construction and combinations of parts hereinafter fully described and claimed, it being understood that various modifications may be resorted to 25 within the scope of the appended claim without departing from the spirit or sacrificing any of the advantages of the invention.

In the accompanying drawings forming part of this specification:

30 Figure 1 is a side elevation of hair collecting apparatus constructed in accordance with the invention and applied to a barber's chair.

Figure 2 is a longitudinal sectional view of the hair suction and storage apparatus.

35 Figure 3 is a plan view of the hair receiving tray.

Figure 4 is a longitudinal sectional view of the tray shown in Figure 3 and showing the position it occupies on the shoulders of the customer.

40 Figure 5 is a cross sectional view taken on the line 5—5 of Figure 4.

Figure 6 is a rear elevation of the mounting bracket for the hair receiving tray.

45 Figure 7 is a perspective view showing the location of the pipe line, lead lines from the various chairs and suction and storage apparatus, in a barber shop.

Figure 8 is a side elevation showing a hair receiving tray and showing a modified form of mounting bracket therefor.

50 Figure 9 is a plan view of a branched hose connection whereby two chairs may be serviced from a single outlet on the main pipe line.

55 Referring now to the drawings in which like

characters of reference designate similar parts in the various views, 10 designates a conventional barber's chair. In carrying out the invention an arcuate tray 11 is provided the same having short inner and outer walls 12 and 13 respectively 5 and a concave bottom 14. The tray is sufficient in size to embrace the customer's neck and is somewhat arched longitudinally so as to conform to the shape of the shoulders, as best shown in Figure 4. The rear of the tray is depressed below 10 the front of the tray so that gravitating hair will roll down the tray to a low central point at the rear of the concave bottom of the tray where an outlet pipe 15 is located.

The tray is adjustably mounted on the barber's chair and for this purpose a pair of superposed eyes 16 are secured to the back of the chair near the left edge thereof as best shown in Figure 6. A tube 17 is confined against the back of the chair by the eyes and is provided at the top with a 20 split ring clamp 18. A rod 19 is telescopically mounted for vertical adjustment in the tube by the clamp 18. The upper end of the rod is bent to extend horizontally. A tube 20 telescopically receives the bent end of the rod and is held in 25 adjusted positions on the rod by a split ring clamp 21 formed integral with the tube. A strap bracket 22 embraces the outlet pipe 15 of the hair receiving tray and adjustably secures the tray 30 for movement forwardly and backwardly on a lug 23 which is formed integral with the eye 24 that receives the tube 20 and is adjustably secured for movement longitudinally of the latter by a screw 25.

A suction hose 26 is provided with a nozzle 27 which receives the rear end of the outlet pipe 15 of the hair receiving tray. The hose is connected to a conventional electrically operated exhaust fan 27' which may be mounted on the top of a casing 28 which is supported upon legs 29. The outlet of the exhaust fan is equipped with a hose 30 which extends downwardly through the top of the casing 28 and is connected to a conventional vacuum cleaner bag 31. The casing is provided with a removable perforated cover 32 which is held in place on top of the container by cleats 33 which are pivotally mounted as shown at 34 to permit removal of the bag. However, as best shown in Figure 1, the cover 35 may be hinged 40 to 45 shown at 36 to the top of the casing 28 and secured to the cover opposite the hinge by a threaded post 37 and wing nut 38.

In Figure 7 there is shown a common exhaust pipe line 39 for all of the barber chairs in a 50 55

barber shop, there being branch pipes 40 leading from each chair to the main pipe line. Preferably the main pipe line is located in front of the mirror 41 of the barber shop so as to be in rear of the chairs. A suction fan 42 is connected to the main pipe line and exhausts the hair from the various hair receiving trays. The exhaust fan is connected with a conventional vacuum cleaner bag 43.

10 Figure 9 shows a nozzle 44 which is adapted to be connected to the main pipe line or to a hose leading to a collecting casing, and is provided with branches 45 which receive the suction hoses of two adjacent chairs. The branches 15 are controlled by valves 46 which may be opened selectively to service either of the two chairs.

In Figure 8 there is shown a modified form of mounting bracket in which the stem 47 is slidably fitted for vertical adjustment in the mounting opening of the conventional head rest after removal of the head rest and clamped therein by the conventional head rest clamp operated by a button 48. The horizontal leg 49 of the bracket receives the beforementioned eye 24 of the strap 25 clamp 22 which secures the hair receiving tray 11 in place. In this type of bracket the bracket is adjustable vertically on the chair back and the

tray is adjustable horizontally toward and away from the chair.

In operation the tray is adjusted to the customer's shoulders and brought into position to embrace the back of the neck. The exhaust fan 5 may now be started and during the cutting of the hair the hair will gravitate into the tray and be withdrawn therefrom into the exhaust hose 26 for delivery to the receiving bag.

From the above description it is thought that 10 the construction and operation of the invention will be fully understood without further explanation.

What is claimed is:

A barber's accessory comprising, a hair trap 15 having short curved diverging arms provided with inner and outer vertical walls and a concave bottom connecting the walls, said arms being adapted to embrace the back of a customer's neck and being arched longitudinally to be supported upon 20 and conform to the shape of the top of the customer's shoulders, the arched contour of the arms promoting gravitation rearwardly of severed hair to a low central point at the rear of the concave bottom, and a suction hose connection 25 at said low central point.

MORRIS HARTZMAN.
